UNITED STATES PATENT OFFICE

GEORGE E. POWERS, OF GREENFIELD, OHIO, ASSIGNOR OF ONE-FOURTH TO WALTER G. COCKERILL, OF GREENFIELD, OHIO

METALLIC SINGLETREE OR DOUBLETREE

Application filed October 29, 1930. Serial No. 492,056.

This invention relates to a metallic singletree or doubletree.

An object of the invention is the construction of a singletree or a doubletree which is 5 comparatively light, but strong, and which is also practical and durable.

Another object of my invention is the construction of each of the main units of the device out of a pipe-like body, with a rod 10 threaded through the ends of said body, and the ends of the rod formed into eyes, which eyes are of a very novel and efficient structure.

With the foregoing and other objects in 15 view, the invention comprises certain novel constructions, combinations and arrangements of parts as will be hereinafter fully described, illustrated in the accompanying drawings, and more particularly pointed out 20 in the appended claim.

In the drawings:

Figure 1 is a perspective view of a doubletree constructed in accordance with the present invention, in which three pipe-like body 25 units are employed, each very similar in general construction.

Figure 2 is an enlarged longitudinal sectional view taken on line 2—2, Figure 1, and looking in the direction of the arrows.

Figure 3 is an enlarged transverse sectional view taken on line 3—3, Figure 1, and looking in the direction of the arrows.

It is to be understood that in making a singletree or a doubletree in accordance with 35 my invention, I construct a singletree on substantially the same principle as the "spreader device" or main support of a doubletree, and this will be more clearly understood in the following description. Therefore, referring 40 to the drawings by reference numerals, I designates a pipe-like body of the spreader device or main support 2 and 3, 3 are the pipe-like bodies of the singletrees, similar in construction to body 1. I utilize a pipe-like 45 body in constructing bodies 1 and 3, because of the simplicity and efficiency thereof. In said bodies 1 and 3, I form near each end and in the inner side a round aperture 4; registering with aperture 4 is an elongated aperture 5, which is formed in the outer side of

said body (Figs. 2 and 3). I use a bar 6 which is provided at its center with a loop 7 and the ends of the bar are threaded through the sets of registering apertures 4 and 5 and the extreme outer portion of the ends are 55 formed into eyes 8. The extreme outer end 9 of each eye is forced by any suitable means 60 into the elongated aperture 5 and the rod 7 is drawn taut through the registering apertures of the pipe-like body, and then is bent 65 down from the position "C", Fig. 2, shown by dotted lines, to its normal position "D" (Fig. 2). This taut drawing of the rod causes the eye to press hard on the points of 70 aperture 5, at "A" and "B", with considerable 75 pressure at point "E", thereby securely locking the eye against spreading or getting out of shape.

The eyes on the pipe-like body 1, as well as the elongated apertures 5, extend in a position parallel to the longitudinal axis of the body, whereas the eyes of bodies 3 and their apertures 5 are positioned transverse to the longitudinal axis, yet the same highly efficient structure or principle is involved in 75 each instance.

A suitable hook 10 is secured in the loop 7 of the rod 6 carried by body 1, and by medium of this hook, the device may be attached to any implement or vehicle or load, 80 as the operator desires.

The loops 7 of the bodies 3 are connected to eyes 8 of body 1 by means of links 11.

In the eyes 8 of bodies 3, hooks 12 are secured for attaching the devices to the traces 85 or trace chains on the draft animals.

By the novel construction of the pipe-like bodies and eyes, the greater the strain exerted on the device, the more secure the eyes are held against opening, or spreading apart, 90 which would be very undesirable.

My hollow tubular or pipe-like bodies can be formed at a minimum expense, with the novel apertures therein, and the simple rods can be quickly assembled with the bodies and 95 the eyes formed by one familiar with my invention.

It will be obvious that the individual singletree of my invention is constructed on the same principle as the large "singletree" 100

or spreader device 2, and hence the three essential units shown in Figure 1 are each susceptible of being covered by what I herein-after claim.

5 While I have described the preferred embodiment of my invention and illustrated the same in the accompanying drawings, certain minor changes or alterations may appear to one skilled in the art to which this
10 invention relates during the extensive manufacture of the same, and I, therefore, reserve the right to make such changes or alterations as shall fairly fall within the scope of the appended claim.

15 What I claim is:

In a device of the class described, the combination of a pipe like body, said body provided with sets of apertures near its ends, each set comprising a round aperture in the
20 inner side of said body and a registering elongated aperture in the outer side of said body, a rod threaded through both sets of apertures, said rod having its ends formed into eyes against the walls of said elongated
25 apertures, and the extreme outer ends of said eyes in parallelism with the portions of the rod in said apertures and seated entirely in said outer elongated apertures, substantially as shown and described.

30 In testimony whereof I hereunto affix my signature.

GEORGE E. POWERS.
